UNITED STATES PATENT OFFICE.

FRANK HERLE, OF CHICAGO, ILLINOIS.

WASHING-MACHINE.

1,099,702.

Specification of Letters Patent. Patented June 9, 1914.

Application filed December 5, 1913. Serial No. 804,853.

To all whom it may concern:

Be it known that I, FRANK HERLE, a citizen of the United States, residing at Chicago, in the county of Cook and State of Illinois, have invented certain new and useful Improvements in Washing-Machines, of which the following is a specification.

This invention relates in general to washing machines and more particularly to machines adapted for washing clothes and may be made either as a family machine, to be operated by hand, or as a larger power-driven machine, for use in commercial laundries.

The primary object of my present invention is to provide an improved mounting for the drum in which the clothes are contained so that this drum can be rotated alternately in opposite directions with the expenditure of a minimum amount of energy or power.

Another object is to so construct the machine that the drum can be readily detached or disconnected from its driving and supporting shafts and be removed from the tank for the purpose of cleaning, repairing or the like.

Other objects and advantages of this invention will be apparent as the same is more fully understood from the following description when considered in connection with the accompanying drawings.

Referring to the drawings, Figure 1 is a side elevation of a washing machine embodying my invention; Fig. 2 is a horizontal sectional view taken on the line 2—2 of Fig. 1; Fig. 3 is a fragmentary sectional view through the drum; Fig. 4 is an enlarged detail view of one of the castings fixed to one end of the drum; Fig. 5 is an enlarged partial sectional view taken on the line 2—2 of Fig. 1; Fig. 6 is a side elevation of a power driven machine embodying my invention, and Fig. 7 is a partial plan view of the machine shown in Fig. 6.

Referring to the drawings, reference character 7 designates the frame of the machine, which is preferably of cast metal construction, shaped to support a tank, or tub, 8, preferably formed of sheet metal, the frame 50 being formed to provide angle flanges 9 with which the tank is slidably engaged so that the tank may be removed bodily from the frame if desired. On the outer face of each end of the frame I have mounted a pair

of rotatable supporting rollers 11 grooved 55 on their peripheries, as indicated by reference character 12, to receive and support large wheels 13, the perimeters of which are shaped, as shown in Fig. 2, to travel in the grooves of the rollers 11. A stub-shaft 14 is 60 fixed in the hub of each wheel 13 so that these shafts extend laterally into the tank 8 through suitable openings in the end walls of the tank.

The clothes to be washed are carried in a 65 rotatable cylindrical drum, designated generally by reference character 15, disposed within the tank. This drum comprises wooden ends and longitudinally extending wooden staves 16 provided with suitable 70 holes 17 through which water may pass as the drum is revolved within the tank. A casting 18 in the shape of a cross providing four intersecting channels is rigidly secured by rivets 19, or otherwise, to radially extending 75 arms 21 which lie against the outer faces of the drum ends and extend substantially to the outer periphery of the drum. The corresponding arms 21 at opposite ends of the drum are connected together by rods 22 80 equipped with suitable nuts 23 which are utilized to draw the arms toward each other to firmly embrace the drum and clamp the same between the arms so that the castings 18 are securely and permanently attached to 85 the drum concentrically therewith.

For the purpose of carrying the clothes upwardly out of the water in the drum when the drum is revolved I have provided a series of longitudinally extending ribs 24 90 projecting inwardly from the periphery of the drum, these ribs being interposed between staves of the drum at suitable intervals, and those ribs between the ends of arms 21 being grooved as indicated by 95 25 to receive the rods 22. One pair of arms 21 consists of a single bar extending entirely across the casting 18 and is provided with a centrally disposed elongated opening 26, and each shaft 14 is flattened at opposite sides, 100 as shown in Fig. 4, to fit these openings so that the drum and shafts are held against rotation relatively to each other. The inner end of each shaft is threaded to receive a nut or cap 27 which is screwed on to the end 105 of the shaft through a central opening provided in the end of the drum. When the ends or caps 27 are screwed tightly on to the

ends of the shafts the shafts are securely and non-rotatably attached to the drum and the drum is thereby supported from the wheels 13 outside the tank. Suitable washers or 5 rings 28, preferably of leather, are disposed on each side of the openings in the end walls of the tank through which the shafts 14 pass for the purpose of preventing water from splashing out around the shafts. It 10 will be obvious that the drum is rotatably supported by wheels 13 on the supporting rollers 11 and that none of its weight is carried by the tank itself. Should it be desirable at any time to remove the drum from 15 the tank this may readily be accomplished by unscrewing the caps 27, whereupon the shafts 14 can be withdrawn from engagement with the drum and the drum can be lifted out of the tank. The drum is provided 20 on its circumference with one or more doors 29 through which the clothes may be inserted and removed and the top of the tank is normally covered by a cover 31 hinged on the frame at 32.

25 Upon one of the shafts 14 outside of its supporting wheel 13 I have mounted a gear wheel 33 which meshes with and is driven by a gear wheel 34 supported upon a shaft 35 carried by the main frame, the gear wheel 30 34 being fixedly connected with a large fly wheel 36 equipped with a handle 37 by means of which the wheel may be rotated in first one direction and then the other. In order to prevent the wheel 13 at the drive 35 end of the machine from accidentally jumping out of the grooves 12 upon reversal of the drum I prefer to employ a guide roller 38 mounted upon a suitable bracket 39 to engage with the wheel 13 at or near its top.

40 It will be understood that the weight of the drum and the clothes therein is carried by the large wheel 13 supported upon the rollers 11 so that the friction incident to the rotation of the drum is reduced to a minimum, with the result that the machine is 45 extremely easy to operate. While I am aware that washing machines comprising rotatable or oscillatory drums are broadly old, nevertheless, I believe that I am the first 50 to produce a machine of this character in which the weight of the drum is so carried that the friction is reduced sufficiently to render the operation of the machine by hand possible.

55 In Figs. 5 and 6 I have disclosed a power operated machine and have shown mechanism by means of which the drum may be rotated in first one direction and then the other from a continuously operating motor.

60 The motor which is indicated in these figures by reference character 41 drives a counter shaft 42 by means of a belt 43 connecting the pulley 44 on the shaft 42 with the driving pulley of the motor. The spur 65 gear 45 fixed on the shaft 42 meshes with and drives a large gear 46 mounted on a suitable bracket 47 of the main frame, and a second spur gear 48, adapted to be connected to the gear 46, meshes with and drives a large gear 49 rotatably mounted at 70 51 on a bracket 52. A segmental rack 53, pivoted at 54, is connected with the gear wheel 49 by means of a link 55 so that as the wheel 49 is rotated the rack is oscillated up and down about its pivot. A gear 56 75 fixed on one of the shafts 14 outside its supporting wheel 13 meshes with the rack 53 and as the rack is oscillated first in one direction and then the other, as previously described, the gear 56 and the drum inside the 80 tank are rotated in first one direction and then the reverse direction.

It will be manifest that by means of the driving mechanism described the high speed of the motor is reduced and transmitted to 85 the drum so that the drum is rotated alternately in opposite directions without jar or shock by reason of the fact that the reversal takes place as the link connection with the gear 49 passes dead center, so that 90 the speed of the drum gradually increases from a dead center point to a maximum and then gradually decreases again; and that by reason of the reduction in speed and because of the manner of supporting the drum 95 the machine can be operated by a very small motor. The motor may also be utilized to operate the wringer 57, if desired, and to this end I have equipped the wringer shaft with a sprocket wheel 58 disposed in alignment with a drive sprocket 59 loosely mounted on the shaft 61 which carries the gear wheels 46 and 48. The gear wheel 46 is fixed on this shaft and gear wheel 48 is loose thereon. A clutch member 62, feathered on the shaft, is adapted to be engaged at will with the clutch member 63 on the gear wheel 48 or with the clutch member 64 on the sprocket wheel 59. A chain 65 connects the sprocket wheels 59 and 58. 100 Any suitable shifting lever may be employed for shifting the clutch member 62 so that the motor can be utilized to operate either the washing machine or the wringer 105 at will.

It is believed that my invention and its mode of operation will be clearly understood from the foregoing without further description and it will be obvious that the 110 mechanical details disclosed are capable of considerable variation and modification within the scope of the following claim.

I claim:

In a washing machine, the combination of a tank having centrally disposed apertures 115 in its ends, a cylindrical drum mounted within said tank, a stub shaft smaller than the apertures in the tank secured to each end of said drum and extending outwardly axially thereof through an aperture in said 120

tank, a large wheel fixed on the end of each stub shaft extending beyond said tank, means engaging the peripheries of said wheels for rotatably supporting said drum in central position within the tank, means engaging one of said wheels for imparting rotation to said wheels and to said drum,

and means for preventing water in the tank from passing about said stub shaft through said apertures.

FRANK HERLE.
